Primary Examiner — Cathron Brooks*Assistant Examiner* — Teddy Falloway(74) Attorney, Agent, or Firm — Daniel W. Sullivan(57) CLAIM

The ornamental design for a golf glove, as shown and described.

DESCRIPTION

FIG. 1 is a plan view of a front portion of the golf glove of this invention;

FIG. 2 is an elevation view of an open wrist-end portion of the golf glove of this invention;

FIG. 3 is an elevation view of a closed finger-tip-end portion of the golf glove of this invention;

FIG. 4 is a medial side-elevation view of the golf glove of this invention; and,

FIG. 5 is a lateral side-elevation view of the golf glove of this invention.

The broken lines shown are included for the purpose of illustrating portions of the golf glove that form no part of the claimed design.

1 Claim, 2 Drawing Sheets(56)
